(57) **CLAIM**

The ornamental design for a folding cat perch, as shown and described.

DESCRIPTION

FIG. 1 is a front perspective view of a folding cat perch showing my new design;

FIG. 2 is a bottom perspective view thereof;

FIG. 3 is a bottom perspective view in another angle thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is an enlarged view of the area labeled 10 in FIG. 1;

FIG. 11 is an enlarged view of the area labeled 11 in FIG. 2;

FIG. 12 is an enlarged view of the area labeled 12 in FIG. 3;

FIG. 13 is an enlarged view of the area labeled 13 in FIG. 4; and,

FIG. 14 is a front perspective view of the folding cat perch in a folded state.

The short dash-dot broken lines in the figures illustrate portions of the folding cat perch that form no part of the claimed design. The long dash-dot broken lines in FIGS. 1-4 represent boundaries for the enlarged views in FIGS. 10-13, and form no part of the claimed design.

1 Claim, 12 Drawing Sheets
